Primary Examiner — Jasmine Mlinarcik

(57) **CLAIM**

I claim the ornamental design for the body shape enhancing apparatus, as shown and described.

DESCRIPTION

FIG. 1 is a top, left, and rear perspective view of a body shape enhancing apparatus in accordance with the present invention;

FIG. 2 is a rear elevational view of the body shape enhancing apparatus;

FIG. 3 is a front elevational view of the body shape enhancing apparatus;

FIG. 4 is a right side elevational view of the body shape enhancing apparatus;

FIG. 5 is a left side elevational view of the body shape enhancing apparatus;

FIG. 6 is a top plan view of the body shape enhancing apparatus; and,

FIG. 7 is a bottom plan view of the body shape enhancing apparatus.

The broken lines along the surfaces of the body shape enhancing apparatus depict claimed stitching.

1 Claim, 7 Drawing Sheets
